UNITED STATES PATENT OFFICE.

HENRY KOCOUREK, OF JERSEY CITY, NEW JERSEY, ASSIGNOR TO JULIA B. STEWART,
EXECUTRIX OF JOHN K. STEWART, DECEASED.

WINDING-MOUNT FOR POWER-SPRING.

1,255,431.

Specification of Letters Patent.

Patented Feb. 5, 1918.

Application filed December 28, 1916. Serial No. 139,371.

To all whom it may concern:

Be it known that I, HENRY KOCOUREK, a citizen of the United States, residing at Jersey City, in the county of Hudson and State of New Jersey, have invented new and useful Improvements in Winding-Mounts for Power-Springs, of which the following is a specification, reference being had to the accompanying drawings, forming 10 a part thereof.

The purpose of this invention is to provide an improved construction for mounting the power spring of a spring motor for winding. It consists in the elements and 15 features of construction shown and described as indicated in the claims.

In the drawings:—

Figure 1 is a partly sectional side elevation of the spring motor embodying this invention, section being made at the line, 1—1 on Fig. 2.

Fig. 2 is a section at the line, 2—2, on Fig. 1.

The drawings show this invention as applied to a spring motor of the character adapted for a spring starter for automobile engines and certain details which appear in the drawings not material to the present invention are the details of such spring starter, 25 not herein claimed. In such spring starters, the starting shaft or power shaft is also the winding shaft shown at 1, having clutch engagement with the spring drum and specifically with the winding mount, 2, by means 30 of a one-way driving clutch, 6, the detail construction of which is immaterial to the present invention. The motor spring, 4, is anchored at its outer end to the casing, 3, by means of the bolt, 5. For this purpose 35 the outer end of the spring is bent to form an eye, 4^a, which is rendered unopenable by bending the spring back upon itself and riveting the end to the body, as seen at 4^b, leaving the eye sufficiently large to be 40 slipped onto the bolt, 5, or to have the bolt passed easily through it after the spring is 45 in position in the casing. The spring mount or drum, 2, which is the hub of the final gear of the winding train partly shown at 2^a, has 50 a longitudinal channel, 2^b, whose sides are preferably abrupt,—that is, approximately radial with respect to the cylindrical mount or drum, to form abrupt shoulders for stopping the key hereinafter mentioned on the 55 end of the spring. The spring, 4, has its

inner coil rendered a closed rigid ring by riveting the end portion securely to the next outer lap of the coil as seen at 4^c, this ring being of such diameter as to be passed easily but without any considerable play onto the 60 drum or mount, 2. For engaging this longitudinal groove or channel, 2^b, the said closed ring, 4^c, formed by the inner coil of the spring, is provided with an interiorly projecting key, 4^d, adapted to enter and engage 65 securely in the said groove, 2^b, of the mount. Preferably this key is formed by folding back the end of the spring upon itself. Inasmuch as the ring, 4^c, fits without any considerable play about the cylindrical mount 70 and is substantially unstretchable, it will be seen that the key formed by the folded-back end of the spring insures the permanent engagement of the spring with the mount without regard to the character of the 75 shoulders of the groove or of the key,—that is, whether they are abrupt for engagement with each other, or otherwise, but it is preferable to have the groove formed with abrupt shoulders as stated, and the key 80 correspondingly formed. This results as to the side of the key which is formed by the end of the spring by reason of the square form of that end; and such abrupt shoulder is approximately obtained at the fold which 85 forms the other side of the key.

The construction above described for securely anchoring the spring to the mount is of especial importance in the case of power springs for such spring motors as are suitable for spring starters for automobile engines, in which the spring is wound up by the running of the power shaft by the engine after it is started, and in which the spring is necessarily so strong and powerful and the mechanism which is driven by it so heavy, that the inertia of the latter when set in motion by the initial unwinding of the spring is liable to be so great that in case of any failure of action of the devices 90 for disengaging the train which connects the starter shaft with the motor spring mount, the continued rotation of said mount after the spring is fully unwound would tear the mount loose from the spring unless 95 the securement were sufficiently substantial to withstand a strain nearly equal to that which could be imposed by the entire power of the motor which is to be started. And a spring of so powerful a character, it will be 100 105 110

seen, can be mounted on the mount and in the casing only when it has first been coiled by power and secured in coiled condition, so as to be handled for mounting it in its place 5 substantially as a solid inert member; that is, the operator in thus assembling it, must not be charged with any necessity for holding the spring coiled; nor can the manner and means of mounting be such as to require the spring 10 to be released at any time in the process; and the anchoring devices or expedients for securing the two ends of the spring to the casing and to the mount respectively, must be such as not to require any springing or 15 flexure of the spring itself in order to effect the engagements. These conditions, it will be seen are met by the structure shown, because the spring being coiled by any suitable mechanism and bound tightly in coiled condition, as by the wire, 15, shown in Fig. 2, 20 the spring becomes an inert mass and can be inserted on the mount and in the casing by movement axially of the shaft, 1, the key, 4^a, easily engaging the groove, 2^b, in the mount as the spring is slid into place; and 25 the spring having been coiled to a predetermined extent so as to bring the eye, 4^a, at the proper radial distance from the axis of the mount, and the shaft being turned the necessary angular distance to be registered 30 with the threaded aperture, 3^a, of the casing,

provided to receive the bolt, 5, the outer member or cap, 3^b, of the casing is applied outside the spring and said bolt, 5, is then inserted through the aperture, 3^a, of the casing and through the eye, 4^a, of the spring, and screwed home. 35

I claim:—

1. In a spring motor, a winding mount for a motor spring consisting of a cylinder having a longitudinal groove of which both sides form abrupt stop shoulders, in combination with a motor spring having its inner coil rendered a rigid closed ring by riveting the end of the spring at its outer lap, and having 45 a rigid with said ring interiorly thereof, a key fitted to said longitudinal channel of the mount.

2. In a spring motor, a winding mount for a motor spring consisting of a cylinder having a longitudinal groove of which both sides form abrupt stop shoulders, in combination with a motor spring having its inner coil rendered a rigid closed ring by riveting the inner end to the next outer lap of the coil, 55 and having said inner end folded back inwardly upon itself to form a rigid key fitted to said longitudinal channel of the mount.

In testimony whereof, I have hereunto set my hand this 24th day of November, 1916. 60

HENRY KOCOUREK.
